OF WHEELING, WEST VIRGINIA, A FIRM.

LUBRICATOR.

1,328,209.

Specification of Letters Patent.

Patented Jan. 13, 1920.

Application filed May 22, 1919. Serial No. 298,871.

To all whom it may concern:

Be it known that I, SAMUEL J. SHARP, a citizen of the United States of America, and resident of Wheeling, county of Ohio, and State of West Virginia, have invented 5 certain new and useful Improvements in Lubricators, of which the following is a specification.

This invention relates broadly to lubricators, and more specifically to a self-acting, or automatic, oiler for journal bearings.

The primary object of the invention is to provide an extremely simple, inexpensive and efficient lubricator which, while generally applicable to the moving parts of machinery requiring lubrication, is designed particularly for use on the journal bearings of the steam-heated cylinder driers employed in textile and paper mills.

As is well known, a high temperature must be maintained in the cylinder driers of textile and paper mill machinery in order that the same shall properly perform their functions, and this inevitably results in such a degree of heat being imparted to the journal bearings of such cylinders that reliable and efficient lubrication of the bearings becomes a matter of prime importance. Further, it is not only essential that the feeding of the lubricant shall be continuous while the journal is in motion, but also that the feeding shall cease during the time that the journal is at rest, both for husbanding the supply and for preventing waste lubricant from flowing over the ends of the cylinders into contact with surfaces which will be engaged by the cloth or paper to the injury of the latter.

It is a purpose of the present invention 40 to supply a device by which provision is made for the proper lubrication of the journal bearings referred to in the manner hereinbefore indicated as essential.

A further object is to provide a lubricator for the application of which to, and the removal of which from, a journal bearing of any ordinary type is the work of an instant, and which has a construction that renders its replenishment when occasion requires and 50 with any desired form of lubricant a task that can be accomplished with facility.

A still further object is to provide a device of the character mentioned embodying a container which is separated interiorly by 55 a division wall into two compartments, of

which one is a reservoir for the lubricant and the other is a receptacle for water resulting from the condensation of steam which may escape into the container past the wick-like feeder.

With these and other objects in view, the invention resides in the structural features which will hereinafter be exemplified, reference being had to the accompanying drawings, in which—

Figure 1 is a side elevation of the invention, illustrating its application to a journal bearing;

Fig. 2 is a longitudinal section of the invention with the lid or cover thereof up-raised; and—

Fig. 3 is a top plan view of the same with the wick removed.

Referring to said drawings, 1 indicates a box-like container the under side of one end 75 of which is preferably curved, as shown at 2, to approximate the curvature of the upper part of the bearing, as 3, with which it is to be associated, adapting it for conformably seating upon such bearing, as shown in 80 Fig. 1. Formed on or carried by the under side of the container adjacent to that end which is reduced in depth by the provision of the curved bottom 2 is a vertically depending stem 4 which is adapted to seat 85 more or less loosely within the usual bore or oiler-opening 5 provided in the top of the bearing for anchoring said container in place. Through seating of said stem in the hole 5, as aforesaid, the device is rendered 90 not only self-supporting, or anchored, in its operative position, but also readily applicable and removable as occasion may require.

Fitted closely in and protruding slightly from the lower end of a vertical bore 6 95 which leads outward through said stem 4 from the interior of the container is one end of a wick 7 which may be of any preferred form and material adapted to conduct a lubricant by capillary action. Said 100 wick has its opposite end disposed within the lowermost part of the container so that it will continue to function as a feeder until either the reservoir has been emptied of its contents or the lubricant has become 105 sealed, or approaches a solid form, to the extent that it can not be conducted by capillary attraction—that is, to the extent that capillarity ceases.

In this connection it is to be noted that 110

the device described is designed primarily as a feeder of a lubricant which at normal atmospheric temperature is a semi-solid and non-flowing grease that is not susceptible 5 at such temperatures to capillary absorption or attraction, but which becomes fluid at a relatively low temperature, as, for instance, from 105° F. to 120° F., the object being to prevent leakage and waste of the lubricant 10 upon the reduction of temperature in the bearing to a point promptly attained following cessation of the journal's motion.

A low transverse partition, or division 15 wall, 8 located slightly rearward of the feed-opening or bore 6 separates the interior of the container into two compartments 9 and 10. The foremost compartment 9 is shallow in depth on account of its location at the front end of the container where the latter is 20 reduced in depth by the provision of the curved bottom 2, while the compartment 10, which is designed as a reservoir for the lubricant, is of relatively large capacity. The partition 8 serves to separate or exclude 25 from the reservoir any water which may collect in the compartment 9 as a result of condensation of such steam as may enter said compartment past the wick 7.

To afford a means of ready escape for 30 such steam as may find its way into the bearing, and thus in a large measure to prevent the entrance of steam to the lubricant container, the stem 4 is made to fit the oil hole 5 loosely and is preferably provided with 35 a flattened face 11.

A lid or cover 12 is provided as a closure for the top of the container, the same being suitably hinged, as upon a pivot-pin 13.

The wick 7 is made of a thickness which 40 renders it tight fitting in the bore 6 through which is protrudes, thus limiting the rapidity of the flow of the lubricant therethrough. To provide for a further restriction or regulation of the flow, I prefer to employ an ordinary wood screw 14 directed vertically upward through the center of the feed end of the wick. Said screw is tightened to further expand the wick within the hollow 45 of the stem, or is loosened to reduce the density of the fibers of the wick within said stem, according as it is desired to increase or decrease the flow. Said screw obviously constitutes an extremely simple, inexpensive, efficient and readily adjustable form of valve 50 by means of which the feeding of the lubricant may be regulated.

What is claimed is—

1. As a new article of manufacture, a 60 journal-lubricating device comprising a lubricant container having its under side undercut in substantial conformity to the shape of the bearing upon which it is to seat, a member depending from said container and adapted to fit loosely in the oiler-hole of the 65 bearing for anchoring said container in

place, said member having a passage leading therethrough from the interior of said container, and a wick disposed within said container and having an end fitted in said passage.

2. As a new article of manufacture, a journal-lubricating device comprising a lubricant container formed independent of the journal bearing and having a portion of its under side arcuately curved to adapt it for 70 conformably seating upon the top of said bearing, a stem depending vertically from said arcuately curved portion of the container and adapted for loosely seating in the oiler-hole of the bearing whereby said container is anchored in place, said stem having a passage leading therethrough from the interior of the container, and a wick disposed within said container and having an end fitted in said passage.

3. A lubricator for journal bearings, comprising a lubricant container adapted to rest upon a bearing and having a depending stem adapted to seat within the oiler-hole of the bearing for anchoring said container in 80 place, said stem having a passage leading therethrough from the interior of said container, a wick disposed within said container and having an end fitted in said passage, and adjustable means directed vertically upward 85 through that portion of the wick which is received in said passage whereby the flow of the lubricant through said wick may be regulated.

4. A lubricator for journal bearings, comprising a lubricant container adapted to rest upon a bearing and having a depending stem adapted to seat within the oiler-hole of the bearing for anchoring said container in place, said stem having a passage leading 90 therethrough from the interior of said container, a wick disposed within said container and having an end fitted in said passage, and a screw directed vertically into 95 said end of the wick whereby the flow of the lubricant through the latter may be regulated.

5. A lubricator for journal bearings, comprising a lubricant container having a portion of its under side arcuately curved to 100 adapt it for conformably seating upon the top of a journal bearing, a stem depending vertically from said arcuately curved portion of the container and adapted for seating in the oiler-hole of the bearing whereby 105 said container is anchored in place, said stem having a passage leading therethrough from the interior of the container, a wick disposed within said container and having an end fitted in said passage, and adjustable means 110 for expanding the wick within said passage for diminishing the flow of lubricant through said wick.

6. A lubricator for journal bearings, comprising a lubricant container having a por-

- tion of its under side arcuately curved to adapt it for conformably seating upon the top of a journal bearing, a stem depending vertically from said arcuately curved portion of the container and adapted for seating in the oiler-hole of the bearing whereby said container is anchored in place, said stem having a passage leading therethrough from the interior of the container, 5
- 10 a wick disposed within said container and having an end fitted in said passage, and a screw directed into the embraced end of the wick whereby the latter may be expanded within said passage for diminishing the rate 15 of flow of the lubricant therethrough.
7. A lubricator for journal bearings, comprising a lubricant container having its under side shaped to conform to the exterior of the bearing, adapting it for resting 20 directly upon the latter, a stem depending vertically from the under side of said container and adapted to seat within the oiler-hole of the bearing for anchoring said container with respect to said bearing, said stem 25 having a passage leading therethrough from the interior of said container, a wick disposed within said container and having an end fitted within said passage, and means separating the interior of said container 30 into two compartments, said means being disposed slightly rearward with respect to the location of said passage.
8. A lubricator for journal bearings, comprising a lubricant container having its 35 under side shaped to conform to the exterior of the bearing, adapting it for resting directly upon the latter, a stem depending vertically from the under side of said con-
- tainer and adapted to seat within the oiler-hole of the bearing for anchoring said container with respect to said bearing, said stem having a passage leading therethrough from the interior of said container, a wick disposed within said container and having an end fitted within said passage, and a partition wall located adjacent to and rearward of the position occupied by said passage whereby the lubricant is prevented from flowing to a point whence it may drain directly through said passage. 40 45 50
9. A lubricator for journal bearings, comprising a lubricant container having its under side shaped to conform to the exterior of the bearing, adapting it for resting directly upon the latter, a stem depending vertically from the under side of said container and adapted to seat within the oiler-hole of the bearing for anchoring said container with respect to said bearing, said stem having a passage leading therethrough from the interior of said container, a wick disposed within said container and having an end fitted within said passage, and a partition wall located adjacent to and rearward of the position occupied by said passage whereby the interior of the container is divided into a water receptacle and a reservoir for the lubricant, the former having said passage leading therefrom. 55 60 65

In testimony whereof, I affix my signature in presence of two subscribing witnesses.
